UNITED STATES PATENT OFFICE

JOSEPH S. KURKOWSKI, OF PITTSBURGH, PENNSYLVANIA, ASSIGNOR TO JONES & LAUGHLIN STEEL CORPORATION, OF PITTSBURGH, PENNSYLVANIA, A CORPORATION OF PENNSYLVANIA

RAIL SECURING MEANS

Application filed July 17, 1931. Serial No. 551,367.

My invention relates to means for securing railway rails in position upon cross-ties.

I am aware that a number of means for accomplishing this object have heretofore been

5 proposed, but, so far as my knowledge extends, all these means have been objectionable in one way or another, either from a manufacturing standpoint or from the standpoint of the operating characteristics. It is the 10 object of the present invention to overcome these objections and to provide a rail securing means comprising a tie-plate and a rail clip which can be manufactured without difficulty at relatively low expense and which will 15 serve its intended purpose effectively throughout a long period of use.

For a complete understanding of the invention, reference is made to the accompanying drawing, in which

20 Figure 1 is a sectional view, taken through the web of a rail having the invention applied thereto, the flange of the rail being broken away and the invention being shown in plan view; and

25 Figure 2 is a sectional view along the line II-II of Figure 1.

Referring in detail to the drawing, the invention comprises a tie-plate 10 adapted to rest upon and be secured to the usual cross-tie 11. Corner holes 12 are provided in the plate 10 for receiving lag screws or screw spikes 13 for securing the plate to the tie.

On opposite sides of the longitudinal center line of the plate, upstruck lugs 14 are formed 25 by punching out a hole 15 from the body of the plate and bending the punched-out material at substantially right angles to the latter. The inner edges of the lugs 14 are spaced from the transverse center line of the plate, which coincides with the center line of the rail, so as 30 to engage the rail flange 16 for the purpose of maintaining a predetermined relative position of the rail with respect to the plate.

In order to secure the rail firmly to the plate 45 10, I employ clips 17 adapted to engage the rail flange 16 and designed so as to be readily secured to the plate. For receiving one end of the rail clips 17, holes 18 are formed in the plate 10. Preferably, the side walls of these 50 holes are tapered and one of them is provided

with a shoulder 19 for a purpose to appear hereinafter. The holes 18 and the shoulders 19 can readily be formed by hot punching and die forming operation.

The rail clips 17 are of substantial U-shape 55 and, when in place, occupy a substantially horizontal position, as shown in Figure 2. One end of the U-shaped clips 17 is bent, as shown at 20, to form a portion for engaging the rail flange. The other end of the clips is 60 given a reverse bend, as shown at 21, and also an outward bend 22. The reverse bend 21 is made such that the width of the bend end, under normal conditions, is slightly greater than the width of the hole 18 at the top of the 65 plate 10.

The position of the clips before being secured to the tie-plates is shown in dotted lines in Figure 2. When in such position, the application of pressure to the region of 70 the bend 22 forces the end 21 of the clip through the upper end of the opening 18, slightly compressing the bent end 21, so that it will pass through the restricted portion of the hole 18. As soon as the bent end 21 has 75 passed through the restricted portion of the hole 18, it expands slightly so that the extreme end of the clip seats under the shoulder 19 in the hole 18. The clip 17 is thereby firmly secured to the tie-plate 10. The application 80 of the clip also stresses the material thereof so that the end 20 exerts a downward pressure on the rail flange 16.

It will be apparent from the foregoing description that the invention is characterized 85 by numerous advantages. In the first place, since the plate is perfectly flat, except for the lugs 14 which are formed by bending up the material from the body of the plate, the latter may be manufactured from flat stock 90 of appropriate thickness. No special roll or shape is necessary and the use of flat stock considerably cheapens the product. The operations of striking up the lugs or punching 95 and forming the holes 18 are quite simple and can be performed without materially increasing the cost of the plate. The clip 17 is made of ordinary bar stock bent while hot to the required shape and practically no finishing operations are necessary thereon. As above 100

explained, the application of the clips to the tie-plates after the rails have been placed thereon can be effected easily.

Although I have illustrated and described herein but a single present preferred modification of the invention, it will be apparent that numerous changes may be made therein without departing from the scope of the invention as set forth in the appended claims.

10 I claim:

1. In a tie-plate, a pair of spaced shoulders struck up from the material of the plate, and a pair of holes each having a shouldered side wall for receiving a resilient, rail securing 15 clamp.

2. In combination, a tie-plate having a hole therethrough provided with a shouldered side wall, and a rail securing clip having an end with a reverse bend, adapted to 20 enter said hole and seat against said shouldered side.

3. Rail securing means comprising a tie-plate having upstruck lugs for positioning a rail thereon and a hole therethrough having 25 one side undercut, and a clip of substantially U-shape seated on said plate substantially horizontally, one end of the clip being bent down to engage a rail flange, and the other end being reversely bent to enter said hole 30 and engage said undercut side.

4. The combination with a rail supporting tie-plate and a hole therein, of a rail-securing clip having one end bent back on itself, curved outwardly and reversed again at its 35 extremity, for entry into said hole and engagement with a side thereof.

5. In a rail-securing clip, an end portion bent back on itself adapted to enter a hole in a tie-plate for engagement with a side thereof, and another portion arched to engage the 40 rail flange with its end.

6. In a tie-plate, a hole therethrough, and a rail clip having a bent back portion turned outwardly and reversely bent to form an end 45 wider than said hole, whereby the end portion may be contracted and forced into the hole to secure the clip to the plate.

7. A rail-securing clip having a turned back end curved outwardly and reversed on 50 itself, adapted to enter a hole slightly less in width than said end, whereby said end is initially contracted and then expands to secure the clip in the hole.

8. The combination with a rail-supporting 55 tie-plate having a hole therein, of a rail clip having a portion engaging the rail flange with its end only and a bent back portion turned outwardly and reversed on itself to form an end of a width normally greater 60 than that of the hole, whereby said end portion, when forced into the hole, contracts initially and effects engagement with the plate.

9. A rail securing means comprising a clip 65 of substantially U-shape, one leg of the clip

being curved in one direction to engage the flange of the rail with its end, the other leg being bent outwardly and reversed on itself for entry into a hole in a tie-plate.

In testimony whereof I have hereunto set 70 my hand.

JOSEPH S. KURKOWSKI.
